G. W. Metcalfe,

Horse Muzzle.

N° 66,375.

Patented July 2, 1867.

United States Patent Office.

G. W. METCALFE, OF HUMMELSTOWN, PENNSYLVANIA.

Letters Patent No. 66,375, dated July 2, 1867.

IMPROVEMENT IN AN APPARATUS TO CURE HORSES OF CRIBBING.

The Schedule referred to in these Letters Patent and making part of the same.

TO ALL WHOM IT MAY CONCERN:

Be it known that I, G. W. METCALFE, of Hummelstown, in the county of Dauphin, and State of Pennsylvania, have invented an improved Instrument to Cure Horses of Cribbing and Sucking Wind; and I do hereby declare that the following is a full and exact description thereof, reference being had to the accompanying drawings, making part of this specification—

Figure 1 being a top or inside view of the instrument as applied to the throat-latch of a bridle.

Figure 2, a vertical section thereof in a plane indicated by the line xx , fig. 1.

Figure 3, a side view of the same.

Like letters designate corresponding parts in all of the figures.

The instrument consists of a metal bow, A, of about semicircular form, and of a size to nearly fit the throat of a horse. In the centre of the bow, inside, a spur, B, situated across the bow, and having two or three sharp points, $b b$, projecting upward, and two spring-shields, C C, secured at their outer ends ff to the ends of the bow, and extending inward close to the spur B, where their inner ends cc curve downward by the side of the blade points, which are ordinarily shielded thereby, all substantially as represented in the drawings. The two ends of the bow are attached by two small screw-bolts, $a a$, and nuts, $d d$, to the throat-latch D of a bridle or halter.

When thus applied, and the bridle or halter around the horse's neck, the instrument fits up under the horse's throat, but the force of the springs C C ordinarily shields the throat from the points $b b$, so that the horse does not feel them. But if he begins to crib and suck wind his throat swells out, depresses the springs C C, which then exposes the points $b b$ to the throat, so that they prick and cause the horse to desist from the act for the time; and by thus being kept applied to his neck he will soon be entirely cured of the pernicious habit. If the bridle is taken off of the horse the instrument can readily be detached therefrom by taking out the two screw-bolts $a a$, and then attaching it to the halter, and *vice versa*; or there may be one of the instruments continually attached to each. The action of the spring-shields is indicated by black and red lines in fig. 3.

What I claim as my invention, and desire to secure by Letters Patent, is—

The combination of the bow A, spur B, and the two spring-shields C C, constructed and arranged as and for the purpose herein specified.

The above specification of my improved apparatus to cure horses cribbing and sucking wind signed by me this 15th day of April, 1867.

Witnesses:

LEVI LITTLE,

JACOB SHOPE.

G. W. METCALFE.
